LUGGAGE HANDLE

Lou F. Marks, Pittsburgh, Pa., assignor to Bruce Molded Plastic Products Inc., Mon Run, Pa., a corporation of Pennsylvania

Filed Sept. 17, 1968, Ser. No. 13,559

Term of patent 14 years

Int. Cl. D8—03

U.S. Cl. D8—154

Fig. 1.

Fig. 2.

Fig. 4.

Fig. 3.

Fig. 5.

*Fig. 6.**Fig. 8.**Fig. 7.**Fig. 9.*Fig. 10.

Fig. 11.

Fig. 12.

Fig. 13.

Fig. 14.

FIG. 1 is a top plan view of a luggage handle showing my new design;

FIG. 2 is a front elevation of FIG. 1;

FIG. 3 is an end view of FIG. 2;

FIG. 4 is a horizontal sectional view along line 4-4 of FIG. 2;

FIG. 5 is a vertical sectional view along line 5-5 of FIG. 2;

FIG. 6 is a front elevation of an embodiment of the luggage handle of FIG. 2 wherein the end lugs are each fitted with a disk-shaped enlargement;

FIG. 7 is an end view of FIG. 6;

FIG. 8 is a horizontal sectional view along line 8-8 of FIG. 6;

FIG. 9 is a vertical sectional view along line 9-9 of FIG. 6;

FIG. 10 is a top plan view of the embodiment shown in FIG. 11;

FIG. 11 is a front elevation of another embodiment of the luggage handle of FIG. 2 wherein the end lugs are fitted with cylindrical trunnions;

FIG. 12 is an end view of FIG. 11;

FIG. 13 is a horizontal sectional view along line 13-13 of FIG. 11; and

FIG. 14 is a vertical sectional view along line 14-14 of FIG. 11.

I claim:

The ornamental design for a luggage handle, as shown and described.
